UNITED STATES PATENT OFFICE.

ARTHUR H. FISCHE, OF INDIANAPOLIS, INDIANA.

NON-GLOSSING SPONGING PRESS-CLOTH.

1,289,142.

Specification of Letters Patent.

Patented Dec. 31, 1918.

Application filed July 5, 1918. Serial No. 243,453.

To all whom it may concern:

Be it known that I, ARTHUR H. FISCHE, a citizen of the United States, residing at Indianapolis, in the county of Marion and 5 State of Indiana, have invented a new and useful Non-Glossing Sponging Press-Cloth, of which the following is a specification, reference being had to the accompanying drawings and to the letters and figures of reference marked thereon.

This invention relates to an appliance that is designed to be used instead of the well known press-cloth commonly employed by tailors and those who press garments or 15 other articles.

In the operations of pressing fabrics it has been found necessary to place a cloth or layer of muslin or "drilling" upon the fabric or garment and then use the pressing-iron or "goose" upon the layer, but it is well known that in such operations there is a tendency to cause the fabric to become glossy, this being aggravated when the garment or portions thereof already have a 20 "shiny" surface. The primary object of this invention is to provide a press-cloth which may be used as above described when pressing fabrics without causing or producing a glossy surface on the fabric, another 25 object being to provide a non-glossing sponging press-cloth which shall be adapted to contribute to the preservation of the "nap" of the fabric or garment which may be subjected to pressing operations, and ob- 30 viate the necessity of using the faulty press-cloth hitherto made use of. A further ob- 35 ject is to provide an improved press-cloth which shall be of such construction as to be not only highly efficient but shall be strong, 40 durable and economical in use and not be costly to manufacture.

With the above-mentioned and other objects in view, the invention consists in a sheet or layer of material of a porous nature 45 adapted to permit steam, generated in pressing operations, to circulate when the sheet is upon the fabric operated on, the sheet or layer being provided on its upper face with ribs to hold the pressing-iron off from di- 50 rect contact with the sheet or layer, a cover for the ribs being arranged upon the latter to guide the pressing-iron on the ribs and prevent the latter from being scorched, the cover being of a relatively less porous char- 55 acter than the sheet or layer, so as to be en-

abled to retard the escape of the generated steam or vapor. The invention consists also further in the parts and combinations and arrangements of parts as hereinafter particularly described and finally pointed out in the accompanying claims.

Referring to the drawings,—Figure 1 is a top plan of the new press-cloth as preferably constructed, a portion of the cover thereof being turned back to expose the essential features of the invention; Fig. 2 is an end view of the press-cloth; Fig. 3 is a fragmentary top plan of the press-cloth minus its cover; Fig. 4 is a fragmentary transverse section of the press-cloth; Fig. 5 is a fragmentary plan of the under side of the press-cloth; Fig. 6 is a perspective view of a well known gas iron for pressing fabrics and shown in operative position in relation to the invention to illustrate a function of the improved construction in press-cloths; and, Fig. 7 is a fragmentary perspective view of the principal part of the new press-cloth.

Similar reference characters in the different figures of the drawings indicate corresponding elements, parts or features hereafter referred to in detail.

The new press-cloth comprises a sheet or layer 1 which is composed of woolen cloth which preferably is of the character of that commonly known as wool undercollar cloth, the sheet therefore being of a spongy consistency and having soft or rough faces. The sheet is made in various sizes, convenient dimensions being nine by twenty-four inches, the edges being left unfinished. The under side of the sheet or layer is left in its natural condition or practically so, in order to insure practically continuous contact with the articles to be pressed. The upper side of the sheet or layer is provided with a plurality of ribs or tracks 2, 3, 4, 5, 6, 7, 8 and 9, these preferably being arranged longitudinally of the sheet and spaced a suitable distance apart, a satisfactory result being obtained when the spaces are approximately one-half inch or less in width, and the ribs may suitably be approximately three-fourths of an inch or less in width and are secured by any suitable means upon the sheet or layer. A cover 10 is provided which preferably is composed of material of the character of the well known white unbleached drilling and corresponds in plan dimensions to the like dimensions of the sheet 1, so as

to lie flat upon and cover the ribs, the cover being suitably secured adjacent to one of the longer edges thereof to the sheet or layer adjacent to one of its longer edges, preferably by means of a row of stitching 11. The ribs or strips of cloth are preferably secured to the sheet 1 by means of rows of stitching 12 and 13 to secure each strip in place. Each rib is preferably composed of the material of which the sheet or layer 1 is composed.

In practical use the article to be pressed is placed upon an ironing board or press board 14 as is customary, and an article 15 which is conveniently illustrated in Fig. 6 is laid flat upon the press board as usual. The plain side of the new press-cloth is laid upon the article 15, so that the ribs shall be upon the upper side of the sheet or layer 1 and the cover 10 upon the ribs. Water is used with a sponge as hitherto, and the pressing-iron 16 is placed upon the cover 10 and moved about thereon to obtain the desired results, the heat from the pressing-iron causing steam or vapor to be generated from the water. The steam or vapor is retained a desired length of time under the cover 10 and is distributed throughout the press-cloth with the most advantageous results. When the pressing-iron is removed and the press-cloth lifted from the fabric article operated on, the under side of the press-cloth has a tendency to lift up or raise the nap of the pressed fabric in a greatly desired manner, the nap being permitted to stand up to an extent in the nap of the under surface of the press-cloth, the thick and spongy press-cloth and the ribs thereon preventing the

smooth-faced cover and the pressing-iron from smoothing down the face of the fabric 40 or garment being pressed.

Having thus described the invention, what is claimed as new is:—

1. A press-cloth including a flexible fabric sheet and ribs on one side of the sheet, all 45 composed of one and the same material, and a cover composed of different material and connected to the sheet to lie upon the ribs.

2. A non-glossing sponging press-cloth comprising a flexible fabric layer having a 50 plurality of flexible fabric strips and also a flexible fabric cover secured thereto, the strips being spaced apart and arranged between the layer and the cover.

3. A non-glossing sponging press-cloth 55 comprising a woolen fabric layer, a plurality of woolen fabric strips spaced apart upon one side of the fabric layer and secured thereto, and a flexible cover secured to one edge portion of the fabric layer and extending over the fabric strips.

4. A sponging press-cloth including a thick and porous layer to lie upon cloth and permit circulation of steam therein, the upper side of the layer having ribs thereon to 65 hold the pressing iron off from the layer, and a relatively thin and smooth cover upon the ribs to guide the pressing iron over the ribs.

In testimony whereof, I affix my signature 70 in presence of two witnesses.

ARTHUR H. FISCHE.
